F. C. SIMMONS

BELT BUCKLE

Filed Feb. 19, 1927

Inventor:
Frederick C. Simmons,
By Not Co. & Sale
Attorney.

UNITED STATES PATENT OFFICE.

FREDERICK C. SIMMONS, OF HIGHLAND PARK, PENNSYLVANIA, ASSIGNOR TO PIONEER SUSPENDER COMPANY, A CORPORATION OF PENNSYLVANIA.

BELT BUCKLE.

Application filed February 19, 1927. Serial No. 169,448.

The invention relates to improvements in belt buckles. The object is to provide an improved construction for maintaining the shape of the face portion and for maintaining the belt in close engagement with the vertical edge or margin of the face portion which is opposite the other vertical edge or margin near which the clamping element engages the belt.

For example the belt buckle, now in common use, comprises a face portion, with portions at the top and bottom bent around back of the face portion and extending a short distance toward each other in planes approximately parallel with the plane of the face portion. One end of each bent-over portion is formed into a bearing for the clamping element which operates on a vertical axis. In order to provide space for the operation of the clamping element, these bent-over portions lie in a plane removed from the plane of the face portion a distance considerably greater than the thickness of the belt, so that when the clamping element clamps the belt to the face portion near one of its vertical margins, the other vertical margin is liable to be separated a substantial distance from the surface of the belt, which detracts from its neat appearance, and forms an edge which is liable to catch upon other parts of the clothing. This is especially the case when the buckle has a greater vertical extension, such as is used with a wide belt.

This objection has been overcome by providing separate channels for the belt at the top and bottom of the buckle, and providing stepped extensions removed a greater distance from the face portion for providing the vertical pivot-bearing for the clamping member.

Referring to the drawings, which illustrate merely by way of example a suitable embodiment of my invention:

Fig. 1 is a view in perspective of a buckle made in accordance with my invention.

Fig. 2 is a section on the line 2, 2 of Fig. 1, showing the belt in place.

Fig. 3 is a section on line 3, 3 of Fig. 2.

Similar numerals refer to similar parts throughout the several views.

The face portion 5 is usually slightly concavo-convex and has a vertical extension greater than its horizontal extension. At the upper and lower ends are portions 6 bent back of the face portion 5 into a plane substantially parallel with the face portion. These bent portions 6, with the adjacent parts of the face portion, form channels 7 for the longitudinal edges of the belt 8. Beyond these portions 6 are extensions 9 substantially at right angles with portions 6 and from these right angled extensions are further extensions 10, the ends of which are formed into bearings 11 for the pivot ends 12 of the clamping member 13. In other words the two extensions or portions 6 and 10, are in stepped relationship, and both in planes approximately parallel with the face portion, the first forming with adjacent face portions the belt channels, while the others have portions bent into pivot-bearings for the clamping member 13. This clamping member 13 engages the belt near one of the vertical side margins 14 of the face portion 5.

In the old construction, where the channels for the belt were considerably wider than the thickness of the belt, the opposite margin 15 of the face portion was not held firmly against the belt, while in the present structure, as shown, the channels 7 are only slightly greater in width than the thickness of the belt, so that the belt, at all times, is held firmly against the margin 15.

This triple bending, or corrugated formation, of the bent-over portions 6, 9 and 10, tend to stiffen the structure so that a light gauge of metal may be used without danger of the buckle becoming distorted.

What I claim is:

1. A belt buckle comprising a face portion, portions at the top and bottom of the face portion bent back of the face portion and forming, with adjacent parts of the face portion, channels for the longitudinal margins of the belt, and further portions bent away from the face portions and then into

a plane approximately parallel with the face portion, said last portions having ends formed into pivot-bearings and a clamping member pivotally engaged with said bearings.

2. A belt buckle comprising a face portion, top and bottom portions bent from and to the rear of the face portion and forming therewith closely fitting belt chan-

nels, further portions bent from the top and bottom portions and stepped away from the face portion in a plane substantially parallel with the plane of the face portion and having extensions forming pivot-bearings and a clamping member pivotally mounted on said bearings. 15

FREDERICK C. SIMMONS.
